UNITED STATES PATENT OFFICE.

JOHN S. BARNES, OF DETROIT, MICHIGAN.

DESIGN FOR AN ADVERTISING CIGAR-BOX OPENER.

SPECIFICATION forming part of Design No. 31,812, dated November 7, 1899.

Application filed July 12, 1899. Serial No. 723,638. Term of patent 14 years.

To all whom it may concern:

Be it known that I, JOHN S. BARNES, of the city of Detroit, county of Wayne, and State of Michigan, have invented and produced a new and original Design for an Advertising Cigar-Box Opener, of which the following is a specification, reference being had to the drawings forming a part thereof.

Figure 1 represents the cigar-box opener in its entirety. Fig. 2 is a plan view showing the face of the hammer. Fig. 3 is a cross-sectional view of Fig. 1 on the line 3 3.

As shown in the drawings, the leading and material features of my design consist of an advertising cigar-box opener having the handle A, the blade B, the panel C, the hammer D, and the claw E. The handle is about one-half inch in width, the sides being straight and parallel, with the outer corners rounded. From its panel portion it gradually slopes to the juncture of the blade. The blade is flat and rounded at its end, its sides straight and parallel. At the juncture of the handle and the blade is the bell-shaped hammer, the hammer proper reaching about three-quarters

across the blade, its larger surface projecting slightly beyond one of the side edges of the blade. From the smaller portion of said hammer is raised a sort of bell-handle, which projects slightly beyond the opposite edge of the 30 blade. In the latter-mentioned edge of the blade is cut a claw. The panel inserted in the handle rests midway between the sides of the handle. Said panel as it appears in the handle has parallel straight sides with straight 35 edges at the ends simply for the formation of right angles, the remaining portion of the ends being convexly rounded. In the panel may be inserted an advertisement visible on one or both sides of the panel. 40

Having described my invention, what I claim as new, and desire to secure by Letters Patent, is—

The design for an advertising cigar-box opener as herein shown and described.

JOHN S. BARNES.
